FIG. 1.

FIG. 2.

FIG. 3.

INVENTOR
George H. Smith
By Horatio E. Bellows

ATTORNEY

UNITED STATES PATENT OFFICE.

GEORGE H. SMITH, OF PROVIDENCE, RHODE ISLAND, ASSIGNOR TO CHARLES D. KENNEY, OF CRANSTON, RHODE ISLAND.

CURTAIN-ROD FIXTURE.

1,347,525.

Specification of Letters Patent.

Patented July 27, 1920.

Application filed May 3, 1920. Serial No. 378,369.

To all whom it may concern:

Be it known that I, GEORGE H. SMITH, a citizen of the United States, residing at Providence, in the county of Providence and 5 State of Rhode Island, have invented certain new and useful Improvements in Curtain-Rod Fixtures, of which the following is a specification.

My invention relates to curtain rod supports and has for its essential objects an extensive frictional or bearing area upon the rod; a minimum of parts; inexpensiveness of construction; and security.

To the above ends essentially my invention consists in such parts and in such combinations of parts as fall within the scope of the appended claims.

In the accompanying drawings which form a part of this specification—

20 Figure 1, a side elevation of my brackets engaging a curtain rod which is shown partially broken away,

25 Fig. 2, a similar elevation of my bracket, showing a portion of the adjacent rod in central longitudinal section,

Fig. 3, a front elevation of the bracket, and

Fig. 4, a section of the rod and bracket on line 4—4 of Fig. 2.

30 Like reference characters indicate like parts throughout the views.

My bracket is cut from a strip of resilient thin sheet metal and the resultant flat blank is bent up into final form. In detail it comprises an oblong base 6 provided at each end with enlargements 7 having perforations 9 to admit attaching screws 10. Upon one lateral edge of the base is an integral arm 12 of flat material twisted into spiral con-

volutions 14 having edges 15. The arm 12 40 is disposed at right angles to the base.

Any usual form of tubular curtain rod 18, either telescoping or integral, and either split or unsplit, may be employed. The edges 15 of the resilient convolute arm 12 45 are a snug fit in the rod. Furthermore the spiral arrangement of the edges 15 which everywhere are in contact with the rod afford a much greater proportionate bearing area than is present in an unbent arm, 50 and insures a firm and noiseless fit. The structure bends itself to formation from a single struck blank by bending so that no substantial expense is involved in its manufacture. The one piece construction affords 55 also a maximum of strength.

I claim:—

1. The combination with a curtain rod, of a bracket comprising a base, and an arm on the base comprising turns engageable 60 with the interior of the rod through the inner circumference.

2. The combination with a curtain rod, of a bracket comprising a base, and a lateral arm integral with the base and disposed at 65 right angles to the base comprising turns or twists whereby the arm engages the rod through the inner circumference.

3. The combination with a tubular curtain rod, of a bracket comprising an oblong 70 base, and a flat twisted arm integral with one side edge of the base comprising turns adapted to engage the rod throughout substantially 360 degrees.

In testimony whereof I have affixed my 75 signature.

GEORGE H. SMITH.
